THE MORRIS PETERS CO., PHOTO-LITHO., WASHINGTON, D. C.

UNITED STATES PATENT OFFICE.

HENRY BRINTON, OF PHILADELPHIA, PENNSYLVANIA.

CIRCULAR-KNITTING MACHINE.

SPECIFICATION forming part of Letters Patent No. 700,730, dated May 27, 1902.

Application filed October 28, 1899. Serial No. 735,013. (No model.)

To all whom it may concern:

Be it known that I, HENRY BRINTON, a citizen of the United States, residing in the city and county of Philadelphia and State of Pennsylvania, have invented certain new and useful Improvements in Circular-Knitting Machines, of which the following is a full, clear, and exact description, reference being had to the accompanying drawings, forming a part of this specification.

This invention relates to improvements in that class of circular-knitting machines wherein the cam-cylinder is provided with devices, termed "pickers," for automatically elevating and depressing certain needles during the operations of widening and narrowing the web, and wherein mechanism is employed for imparting the requisite continuous rotary and reciprocating rotary motions to said cylinder at predetermined intervals, the continuous movement being effected during the production of tubular work—as, for example, the leg or foot of a stocking—and the reciprocating movement being had during the knitting of fashioned work—as, for example, the heel or toe of the stocking. In this class of machines during the knitting of tubular work the entire circular series of needles in the needle-cylinder are in active position and are actuated by the revolving knitting-cams. Preparatory to the production of fashioned work about one-half of the series are raised above the active path of said cams and the latter are reciprocated to and fro, the end needles of those remaining in action being lifted out of action in alternate succession until the requisite narrowing of the web has been accomplished, whereupon the said needles are depressed into action in inverse order to the last preceding operation, so as to effect a corresponding widening of the web. This being done, all the needles are moved into action and the knitting of tubular work is resumed.

The leading features of my invention relate, first, to a novel clamp-support for the needle-cylinder; secondly, to improved picker-controlling mechanism; thirdly, to cam devices for shifting the half-series of needles out of and into action, as desired; fourthly, to mechanism for automatically stopping and controlling the operation of the machine at certain stages of the knitting operation; fifthly, to

means for automatically regulating the length of the stitches at predetermined intervals, and, finally, to various novel features of construction and combinations of parts, which will be hereinafter particularly described and claimed.

In the drawings, Figure 1 is a plan of the machine. Fig. 2 is a rear elevation thereof. Fig. 2^a is a detail of the link connection between the stitch-regulating lever and the rock-shaft under the control of the pattern mechanism. Fig. 3 is an end view of the machine. Fig. 4 is a longitudinal vertical section on the line 4 4 of Fig. 1. Fig. 5 is a development of the exterior of the portion of the cam-cylinder carrying the picker mechanism, the elevating-pickers being represented in active position and the depressing-pickers in inactive position. Fig. 6 is a similar view showing two sets of pickers in reverse condition. Fig. 7 is a view of the inner face of the portion of the cylinder and visible parts shown in Fig. 5. Fig. 8 is a development of the exterior of that portion of the cam-cylinder carrying the diagonal lifting and lowering cams, showing the rocking head and its coacting parts for controlling the positions of said cams in relation to the cylinder. Fig. 9 is a detail of the inner side of the cylinder, showing the diagonal cams just referred to. Fig. 10 is a partial vertical section on the line 10 10 of Fig. 8. Fig. 11 is a partial horizontal section on the line 11 11 of Fig. 10. Fig. 12 is a sectional detail of the adjustable support for the needle-cylinder and of the mechanism for rendering the pawls active and inactive periodically. Fig. 13 is a vertical section on the line 13 13 of Fig. 12. Fig. 14 is a transverse section on the line 14 14 of Fig. 13. Fig. 15 is a sectional detail of the trip devices for the belt-shipper, showing also a portion of the supplemental stitch-regulating mechanism and the pattern-chain therefor, as on the line 15 15 of Fig. 1. Fig. 16 is a similar detail of one of the elevating-pickers and a portion of the cam-cylinder, as on the line 16 16 of Fig. 5. Fig. 17 is a like detail of the rock-shaft for setting the picker-controlling slides, as on the line 17 17 of Fig. 1.

1 designates the bed of the machine; 2, the fixed needle-cylinder; 3, the rotatable cam-cylinder, and 5 the driving-shaft, provided

with a bevel gear-wheel 6, which coacts with the lower toothed portion 7 of the latter cylinder.

8 is a clamping-ring which supports the needle-cylinder fixedly. This ring is adjustably mounted on the bed-plate and has certain provisions, hereinafter recited, for vertical adjustment. The lower portion of the ring is fitted within the usual circular opening of the bed-plate, the projecting upper portion being split vertically, as at a, and horizontally, as at b, to afford two expansible jaws 9 9. Journaled in the lower portion of the ring is a vertical shaft 12, which extends between the opposing edges of the two jaws, the interposed portion of the shaft being laterally flattened, as at 18, throughout the length of the jaws to afford an elongated eccentric or cam, whereby when the shaft is properly turned the jaws will be expanded to clamp the surrounding needle-cylinder, and when the shaft is reversibly turned the jaws contracting will release the cylinder. The lower end of this shaft is provided with a suitable handle 19, whereby it may be manipulated. This construction of clamp is simple, inexpensive, and effective.

20 20 are the elevating-pickers, and 21 21 the depressing-pickers, properly disposed, as 30 usual, in respect to the knitting-cams, which pickers are of the type that are fulcrumed exteriorly of the cam-cylinder and extended therethrough in a manner to be movable into and out of the paths of the needle-heels to 35 act upon the latter and be acted upon thereby. In the present instance the elevating-pickers each comprise a crank-lever 22, fulcrumed at the upper end of an arm 23, which is pivoted on the exterior of the cylinder. 40 The lower arm of the crank-lever is provided with a slot 24, to which is fitted a pin or stud 25 on the wall of the cylinder, while the upper arm of the lever is provided with a notched projection 26, which extends through a slot 45 in the wall of the cam-cylinder, so as to lie immediately above the adjacent stitch-cam 27 and to be movable between the outer end of the latter and the opposing upper end of the central V-cam 28. A suitably-disposed 50 torsional spring 29, secured at its respective ends to the cylinder and arm, tends normally to maintain the notched portion of the crank-lever seated at the outer end of the stitch-cam. When the lever is in this position, the 55 notch thereof lies in the track of the active needle-heels, so that in the rotation of the cylinder the first opposing needle-heel will be engaged by said lever and raised thereby above the path of the knitting-cams in the usual manner. The lever upon the disengagement of the needle therefrom drops yieldingly upon the heels of the remaining active needles and rides thereon until it clears the latter, whereupon the lever assumes its normal position in readiness for a succeeding action. The two elevating-pickers likewise act upon and are acted upon by the opposing end

needles in alternate succession until the requisite number of needles have been moved out of action.

70 The depressing-pickers each embody a partially-rotatable arm 30, slidably mounted on a post 31 on the exterior of the cylinder and held in operative position by the pressure of a spring 32 and by the coacting beveled walls 75 of a slot 33 in the body of the cylinder. The slot 33 is preferably A-shaped, the apex thereof lying above the plane of the knitting-cams. The free end of the picker extends through the slot and is provided with a needle-engaging notch or recess 34. This end of the picker is maintained normally at the apex of the slot by means of the spring 32, which, encircling the post, bears against shoulders on the arm and post, respectively. When in this position, such end will engage the first opposed needle-heel in its path and shift it down into the path of the knitting-cams and thereupon release it, the picker then riding yieldingly against the under sides of the heels of the remaining elevated needles, and finally escaping the latter at the end of the stroke and resuming its previous position in readiness for a succeeding action. Preparatory to the narrowing operation both depressing-pickers are 95 set below the plane to be occupied by the heels of the upthrown needles, so that such pickers will move idly below such heels. The two depressing-pickers are simultaneously moved into or out of action and likewise act 100 upon and render active the opposing end needles of the inactive series in alternate succession.

On the external wall of the cam-cylinder are 105 two oppositely-movable slides 34 34, which are constructed and arranged to coact with the respective sets of pickers to render them idle and active at predetermined intervals. These slides comprise two horizontally-movable plates or strips having pin-and-slot connections 35 with the cam-cylinder. They are disposed between the depressing-pickers and are connected by means of links 36 with a head 37 on one end of a horizontal rock-shaft 38, which is mounted in a bearing at the base 110 of the usual thread-guide post 38^a, whereby when said shaft is properly turned the slides 115 may be moved toward or from each other. The outer ends of the slides are oppositely beveled, as at 39, and are so disposed in relation to the respective picker-arms 30 that when the slides are moved outward their beveled ends impinge against the opposing arms and force the latter out of active position. (See Fig. 5.) When the slides are retracted, 120 the picker-arms 30 resume their normal or active position. One of the slides is provided with a lug 40, which depends below the plane of the upper arm of the adjacent picker-lever 22 in such manner that when the slide is retracted its lug will abut against said lever and raise it out of active position. The other slide 125 is provided with a pivoted dog or latch 41, the forward or free end of which lies above

the plane of the adjacent elevating-lever 22 when the latter is in active position, so that when the slide is retracted to permit the movement of the depressing-picker into active position said latch or dog will be set directly above the lever 22. A suitably-disposed spring 42, secured to the slide and to the dog, maintains the latter yieldingly in place. Such movement of the slide is effected just before the last stroke of the cam-cylinder during the narrowing operation. Hence when the elevating-picker engages the last needle to be thrown out of action the nose of lever 22 in its upward movement will abut against such latch and raise it against the pressure of the spring, the nose thereupon clearing the latch, which latter, resuming its normal position, will prevent the return of said picker to action. (See Fig. 6.) The dog 41 is provided at its shorter end with a lip or stop 41^a, which takes against the lower edge of the adjacent slide, and thereby prevents the dog from dropping. During the knitting of tubular work both slides are in retracted position, the elevating-pickers thus being maintained in the inactive condition and the depressing-pickers occupying their normal position. Preparatory to the narrowing operation the rock-shaft 38 is turned by hand to project the slides endwise from each other, and thereby free the pickers to permit them to assume their active position and at the same time depress the pickers 21 into inactive position. Before the final stroke of the narrowing operation the rock-shaft is turned in an opposite direction, so as to retract the slides and effect the reversal of the two sets of pickers, as above stated. The latter movement of the rock-shaft is automatically accomplished by means of a cam-head 43, which is at the proper time moved into the path of a toe 44 on the end of a rock-shaft through the instrumentality of pattern mechanism, which will be hereinafter described. This rock-shaft is provided with suitably-disposed studs 45, 45, which are designed to abut against a portion of the post or bracket 38^a, and thus limit the throw of said shaft in either direction. The periphery of the shaft is also provided with two flattened portions *x* and *y*, against which is adapted to bear a spring-actuated stud 46, fitted in said post or bracket, whereby the shaft is temporarily locked in either position to which it may be set. In the present instance a flat spring 46^a, which is affixed to said post or bracket, presses yieldingly against the lower end of the stud and maintains it normally in contact with the rock-shaft. (See Fig. 17.)

47 48 are two oppositely-inclined cams fitted in close proximity to each other in diagonal slots in a plate 49, set in the wall of the cam-cylinder. These cams are independently movable horizontally into and from the interior of the latter. During the knitting of tubular work both cams are retracted. Preparatory to the fashioning operation the cam 47 is projected into the cylinder in a

manner to act upon and raise out of action the half-series of needles above referred to. This being accomplished, the cam 47 is retracted. In the final stroke of the cam-cylinder during the completion of the fashioning operation the cam 48 is projected into the cylinder, so as to act upon and return to action the half-series of needles previously up-thrown, whereupon the cam 48 is returned to its normal position. The cams 47 and 48 each comprise a plate provided with an outwardly-projecting stem 50, having a laterally-extending stud 51, against which bears a retracting-spring 52, set in a socket in the plate. Fulcrumed on the plate at a point intermediate the stems of the two cams, so as to swing in a vertical plane, is a rocking head 53, which is provided on its inner side with two bevels or cam portions 54, against which bear the outer ends of the said stems in such manner that when the head is in horizontal position both cams will be retracted, and that when it is rocked to the right or the left the corresponding cam will be projected into the cylinder by the action of the bevel against the opposing stem. The rocking head is provided with an extension 55, which affords a handle whereby it may be manipulated by the attendant so as to set the lifting-cam in action. It is also provided with an inclined lower edge 56, which is adapted during the rotation of the cam-cylinder to coact with an A-shaped cam-piece 57, fixed on the bed of the machine, and thereby shift the rocking head into normal position. The head is also equipped with a depending tappet-arm 58, which is adapted at the completion of the fashioning operation to coact with a movable trip-lever 59 in a manner to shift the depressing-cam 48 into action. This trip-lever is carried by the arm of a rocking frame 60, which is fulcrumed in lugs 61 on the bed-plate, another arm 62 of said frame being extended adjacent to the pattern mechanism and adapted to be actuated thereby in a manner to move the trip-lever into action or permit it to become inactive, as hereinafter described.

Referring to the mechanism for automatically stopping and controlling the operation of the machine at certain stages of the knitting operation, 63 64 are two pattern-chains, the former of which may be termed a "leg-and-foot" chain and the other a "heel-and-toe" chain. These chains are hung upon sprocket-wheels 65 65, which are loosely mounted on a rock-shaft 66, having its bearings in the bed of the machine. On the hubs of said wheels are ratchet-wheels 67 67, engaged by two pawls 68 68, respectively, carried by a common arm 69, fixed on the rock-shaft 66. This shaft is operatively connected with the swinging radius-bar 70, herein-after described, and continuously rocked thereby. In the present instance the rock-shaft is provided at one end with a depending arm 71, which is connected by means of

a link 72 with the bar 70. A means is provided whereby the said pawls may be engaged with and disengaged from their respective ratchet-wheels in alternate succession, so that the chains may be actuated alternately. This means consists of two bell-crank levers 73, loosely mounted on the shaft 66 and provided with sector-like arms 74, which are independently movable below the pawls, so as to raise the latter out of action. The longer arms of these levers are pivotally connected, as at 75, with two vertical slides 76 76, respectively, which are fitted to guides 77, depending from the bed-plate. These slides are socketed, as at 78, for the reception of studs 79 on the respective arms of a centrally-pivoted rock-lever 80, whereby through the movement of said lever the slides may be moved in opposite directions to each other and the crank-levers be correspondingly actuated to effect the action and inaction of the respective pawls. The pivot-stud 81 of this lever is provided with a crank 82, which is connected by means of a link 83 with another crank 84 on a rock-shaft 85, extending below and at right angles to the main shaft. This rock-shaft is pivotally connected by means of a lever 86 to a clutch member 87, splined on the main shaft, to the end that when said clutch member is shifted either to the right or left the rock-shaft is partially turned and the rock-lever 80 likewise actuated.

Sleeved on the main shaft are the usual fast and loose pulleys 88 89, respectively. There is also sleeved on said shaft a pinion 90, with which coacts a sector 91, carried on the upper end of the vertical radius-bar 70, that is pivoted at its lower end to the standard of the machine. This bar is longitudinally slotted, as at 92, to receive the wrist-pin 93 of a crank-wheel 94, which is mounted on a secondary shaft 95, journaled below the main shaft. The secondary shaft is provided with a spur-wheel 96, which gears with and is continuously driven by a pinion 97 on the sleeve of the fast pulley, thus effecting the oscillation of the radius-bar and its sector, and the latter in turn reciprocating the pinion and sleeve with which it is engaged. The clutch member is interposed between the sleeves, respectively, so that it may be engaged with either of them at will. In the present instance the inner ends of the sleeves are provided with socketed collars 98 99, respectively, and the opposing faces of the clutch member are provided with spring-actuated studs 100, which are adapted to register with the sockets in the collars when the clutch member is properly shifted.

From the foregoing it will be seen that when the clutch is engaged with the sleeve of the fast pulley the driving-shaft and, perforce, the cam-cylinder will be continuously rotated and that when the clutch is engaged with the sleeve of the pinion 90 the said shaft, and therewith the cam-cylinder, will be reciprocated.

Bearing against one edge of the lever 86, by which the clutch member is controlled, is a spring-actuated rod 101, that is slidably fitted to an orifice in the standard, whereby the said lever is normally held by said rod in a position to engage the clutch member with the sleeve of the fast pulley. This lever is provided with a lateral stud or projection 102, below which extends a vibratory latch-arm 103, provided with a suitably-located notch 104, with which said stud or projection interlocks when the lever is shifted to engage the clutch member with the sleeve of the oscillating pinion 90, the latch-arm thereupon locking the lever 86 in place in opposition to the spring-rod. The latch-arm is carried by a rock-frame 105 on the bed-plate, one member 106 of which frame extends adjacent to the heel-and-toe chain. This chain is provided with a suitably-disposed projection 107, which is designed at a predetermined interval to abut against the said member and lift the same, thus depressing the latch-arm and freeing the lever 86, whereupon said lever, with its connections, is thrown to its normal position by the action of the spring-pressed rod. When the fast pulley is clutched to the main shaft, as above described, the position of the rock-shaft is such that the pawl 68 for the leg-and-foot chain is in action, while the other pawl is idle, and when the pinion is clutched to the main shaft the position of the rock-shaft 81 is reversed and likewise the respective pawls.

108 is the belt-shipper, by means of which the driving-belt is transferred from one pulley to the other, as desired. This shipper includes a horizontally-movable rod 109, which is suitably guided in the standard of the machine. This rod is normally held in position to maintain the belt upon the loose pulley by the action of a spring 110, which, encircling the rod, bears against a collar 111 on the latter and against the standard. Pivoted to the block is one arm, 112, of a toggle-lever, the other arm, 112^a, thereof being affixed to a forward-extending rock-shaft 113, which is journaled in lugs on the side of the gear-case. The forward end of this shaft is provided with a handle 114, whereby preparatory to the starting of the machine the shaft may be turned by the attendant to throw the shipper toward the fast pulley, against the compression of the spring, the toggle upon passing its center locking the shipper thus adjusted. Extending from the toggle-arm 112^a is a toe 115, the free end of which lies directly above a boss or shoulder 116 on the lower end of a vertically-movable rod 117, that is fitted in a suitable guideway in the bed-plate, whereby the toggle-lever is locked in the position shown to maintain the belt upon the fast pulley. On the upper end of this rod is a lateral lug 118, which extends adjacent to the leg and foot chain, the latter being provided with a suitably-located projection 119, which at a certain time impinges against said lug

and raises the rod 117. The shoulder on the lower end of the latter thus lifts the opposing toe and trips the toggle-lever, whereupon the shipper, resuming its normal position, transfers the belt from the fast to the loose pulley, and in consequence arrests the operation of the machine. This action takes place at the completion of the leg and the foot portions of the stocking. When the machine has been stopped, as just described, the attendant turns the rocking head 53 by hand to project the diagonal lifting-cam 47 into the cylinder, and likewise turns the rock-shaft 38 to shift the slides 34 in a manner to throw the depressing-pickers down out of action and release the other pickers, which latter in consequence drop yieldingly upon the heels of the needles. He then moves the clutch, (against the action of the spring-rod,) so as to release the fast pulley from and lock the pinion 90 to the main shaft. The cam-cylinder is thereby reciprocated. In one stroke the lifting-cam impinges against and raises out of action one-half of the series of needles, whereupon the beveled lower edge of the rocking head rides upon the stationary cam 57, and is thereby moved to effect the retraction of the lifting-cam. When the elevating-pickers reach the open space from which the needles have been raised, said pickers assume their active position, and hence during the succeeding strokes of the cam-cylinder the end needles in action are lifted above the path of the knitting-cams, as above described, until the requisite narrowing has been accomplished. Before the final stroke in the narrowing operation a suitably-located projection 120 on the pattern-chain 64 engages the rock-shaft 43^a of the cam-head 43, and thereby moves the latter into the path of the toe 44 on the outer extremity of the rock-shaft 38 to effect the reversal of the two sets of pickers, as previously described. When the projection 120 escapes the shaft 43^a, the cam-head resumes by gravity its normal or retracted position. The reciprocations of the cam-cylinder continue and the depressing-pickers act upon the previously up-thrown needles to move them into action at the proper intervals and effect the requisite widening of the web. When all these needles have been returned to active position and the formation of the heel thereby completed, a projection 121 on a link of the moving pattern-chain 64 coacts with the arm 62 of the rocking frame 60, which carries the pivoted trip-lever 59, above referred to, thus raising the latter into the path of the depending tappet-arm 58 on the rocking head. Hence this arm during the stroke of the cam-cylinder abuts against the trip-lever and effects the movement of the rocking head sufficiently to project the depressing-cam 48 into the cylinder, which cam thereupon acts against and returns to action the half-series of idle needles. The entire circular series of needles are now in active position. The fixed cam 57 coacts with the beveled edge of the rocking head, as before, to return said head to a central or neutral position, in which case both diagonal cams 70 are retracted. When the projection 121 on the pattern-chain 64 escapes the frame 60, the latter and therewith the trip-lever resume by gravity their normal or inactive position, whereupon the projection 107 on the chain coacts with the frame 105, that carries the latch-arm 103, thus partially turning said frame and depressing the latch-arm in a manner to release the clutch-lever, whereupon the latter, resuming its normal position, disengages the clutch from the sleeve of the reciprocating pinion and engages it with the sleeve of the fast pulley. This being done, continuous circular knitting is carried on to form the foot of the stocking, at the completion of which the operation of the machine is automatically arrested, as before, and the picker-controlling mechanisms are actuated for the formation of the toe precisely as above described in regard to the formation of the heel. Upon the completion of the toe the clutch is automatically unlatched by the action of the projection 107 on the pattern-chain 64 and reengaged with the sleeve of the fast pulley, thus proceeding with the knitting of a series of tubular courses until the operation of the machine is arrested.

Provision is had for automatically regulating the length of the stitches at predetermined intervals—that is, in the formation of the heel and toe the stitches are slightly longer than in the production of the leg. This is accomplished by making the needle-cylinder vertically adjustable in respect to the cam-cylinder and providing a vertically-swinging lever 122 for effecting the requisite adjustments. This lever is pivoted at one end thereof to a bar 123, depending from the bed of the machine, the opposite end of the lever resting on an arm 124 on the rock-shaft 85, with which the clutch is connected. The clamp 8, above described, which supports the needle-cylinder, is provided with a sleeve 126, which is slidably fitted to a depending post 127 on the bed-plate. The post projects below the sleeve and is screw-threaded for the reception of a nut or nuts 128, upon which the sleeve rests. By adjusting these nuts up or down the lowest position of the needle-cylinder may be nicely regulated. The lower portion of the post is centrally perforated for the passage of a stud 129, the upper end of which is connected with the sleeve by a transverse pin 130, which extends through a slot 101^a in the post, the lower end of the stud resting upon a set-screw 131 in the body of the lever. By this construction it will be seen that when the clutch is shifted preparatory to reciprocating work the arm 124 on the rock-shaft 85 will slightly raise the lever 122 and force the needle-cylinder, thus increasing the length of the stitches, and that when the

clutch is returned to its normal position for circular work the lever and needle-cylinder will resume their original position.

As during the knitting of long hosiery it is desirable that the length of the stitches in the calf and upper portion of the leg be greater than that of the stitches in the ankle portion, I provide a supplemental mechanism whereby the stitch-regulating lever is raised for a proper period as follows: 132 is a rock-shaft mounted in brackets or lugs 133, depending from the bed-plate. On one end of this shaft is pivoted an arm 134, provided with a depending lug 135, against which bears a set-screw 136, fitted to a fixed toe or projection 137 on the shaft. By adjusting this set-screw the angle of the arm in respect to the shaft may be nicely regulated. Pivoted to the arm is the upper end of a link 138, the lower end thereof being extended loosely through the free end of the lever 122 and being provided with a set-nut 139, that takes against the under side of the latter for the purpose of adjustment. On the opposite end of the rock-shaft is fixed a depending arm 140, Fig. 15, that lies adjacent to the leg and foot chain 63 in the path of a series of relatively arranged high links 141 on the latter, whereby at a given time the said arm is moved outward and so maintained for a proper period, thus partially turning the rock-shaft and slightly raising the stitch-regulating lever. When the links 141 escape the arm, the parts controlled thereby resume their normal position.

As a simple and efficient means to lock the clutch intermediate the sleeve of the rotary pinion and of the fast pulley, and thus permit the cam-cylinder to be idle even though the driving-belt be upon said pulley, I mount in suitable lugs 142 on the bed-plate a pin 143, which may be moved into and from the path of the clutch-lever 86. The pin is projected normally into such path by a spring 144, which, encircling the pin, bears against a shoulder 145 thereon and against one of the lugs. This lug is provided with a slot 146, and the pin is furnished with a suitably-located stud 147, to the end that when the pin is retracted against the compression of the spring the stud thereon may be drawn through the slot and by a partial turn of the pin seated against the outer face of the lug in a manner to retain the pin temporarily retracted.

I claim—

55. 1. In a knitting-machine, the combination with the bed-plate and the needle-cylinder, of a support for the latter provided with clamping-jaws, and a shaft provided with an eccentric portion interposed longitudinally between the edges of said jaws, substantially as described.

2. In a knitting-machine, the combination with the bed-plate and the needle-cylinder, of a support for the latter, comprising a ring provided with a projecting upper portion split vertically and horizontally to afford two expansible jaws, and a vertical shaft journaled

in the lower portion of the ring and extended between the opposing edges of said jaws, such extended portion being flattened to afford an elongated eccentric or cam, substantially as described.

3. The combination with the cam-carrier, its knitting-cams, a normally active depressing-picker, and a normally active elevating-picker, of a movable member mounted on said carrier and adapted to engage and render inactive the depressing-picker, and to release the same and permit it to return to action, and a yielding latch on said member adapted to be moved thereby into and from the path of the elevating-picker, substantially as described.

4. The combination with the cam-carrier, its knitting-cams, a normally active depressing-picker, and a normally active elevating-picker, of a movable member mounted on said carrier and adapted to engage and render inactive the depressing-picker, and to release the same and permit it to return to action, a vibratory latch or dog pivoted on said member and movable thereby into and from the path of the elevating-picker, and a spring to maintain said latch or dog in a normal position in respect to said member, substantially as described.

5. The combination with the cam-carrier, its knitting-cams, a normally active depressing-picker, and a normally active elevating-picker, of a slide on said carrier adapted to engage and render inactive the depressing-picker, and to release the same and permit it to return to action, and a yielding latch on said member adapted to be moved thereby into and from the path of the elevating-picker, a rock-shaft, and a connection between the same and said slide, substantially as described.

6. In a knitting-machine, the combination, with a cam-carrier, its knitting-cams, a set of normally active depressing-pickers, and a set of normally active elevating-pickers, of two oppositely-movable slides one of which is provided with portions which coact with and control the active and inactive positions of one picker of each set, and the other of which slides is provided with a portion which controls the active and inactive positions of the remaining depressing-picker, and with a yielding latch or dog which is movable into and from the path of the remaining elevating-picker, together with means for actuating said slides, substantially as described.

7. In a knitting-machine, the combination with the cam-carrier, of two oppositely-inclined cams thereon movable in a horizontal plane into and from the interior of the carrier, outwardly-extending stems on said cams, springs to maintain the cams normally retracted, and a rocking head movable in a vertical plane and provided on its inner face with bevels or cam portions which take against the outer ends of the respective stems, substantially as described.

8. In a knitting-machine, the combination with the cam-carrier, of two oppositely-inclined cams thereon movable into and from the interior of the carrier, outwardly-extending stems on said cams, springs to maintain the cams normally retracted, and a rocking head movable in a plane at right angles to the path of said cams and provided on its inner face with bevels or cam portions which 5 take against the outer ends of said stems, a fixed cam adapted to coact with said head to set it in a neutral position, a tappet-arm on said head, trip mechanism, and means whereby it may be moved into and from the path 10 of said arm, substantially as described.

9. In pattern mechanism for knitting-machines, the combination with a rock-shaft, and means for actuating the same, of two independently-movable ratchet-wheels thereon, 15 pattern devices adapted to be intermittently actuated by said wheels, arms affixed to said shaft carrying pawls adapted to coact with the respective wheels, and means whereby the said pawls may be moved into and out of 20 action in alternate succession.

10. In pattern mechanism for knitting-machines, the combination with a rock-shaft, and means for actuating the same, of two independently-movable ratchet-wheels thereon, 25 pattern devices adapted to be intermittently actuated by said wheels, arms affixed to said shaft carrying pawls adapted to coact with the respective wheels, rock - levers loosely mounted on said shaft and provided with sector-like arms movable below and from the 30 respective pawls to render the latter idle and active in alternate succession, and means for shifting said levers in opposite directions to each other at predetermined intervals.

11. In pattern mechanism for knitting-machines, the combination with a rock-shaft, and means for actuating the same, of two independently-movable ratchet-wheels thereon, 40 pattern devices adapted to be intermittently actuated by said wheels, arms affixed to said shaft carrying pawls adapted to coact with the respective wheels, rock - levers loosely mounted on said shaft and provided with sector-like arms movable below and from the 45 respective pawls to render the latter idle and active in alternate succession, reciprocating slides, a rock-lever connected with said slides and adapted to move them longitudinally in opposite directions to each other, and means 50 for operating said lever.

12. In a knitting-machine provided with narrowing and widening mechanism, the combination with the needle-cylinder, the cam-cylinder, the driving-shaft geared with the latter, fast and loose pulleys on said shaft, a driving-belt, a shipper therefor, means whereby said shipper is held normally adjacent to the loose pulley, means whereby it may be temporarily held adjacent to the fast pulley, 60 a reciprocating rotary mechanism, gearing between the same and the fast pulley, a clutch whereby the said reciprocating mechanism

and the fast pulley may be thrown into and out of action in respect to the shaft in alternate succession, means whereby said clutch 70 normally locks the fast pulley to the shaft, a latch device whereby said clutch may be temporarily engaged with the reciprocating mechanism, a rock-shaft, means for actuating the same, two independently-movable ratchet-wheels on said rock-shaft, pattern mechanism adapted to be intermittently actuated by said wheels, arms on said rock-shaft carrying pawls adapted to coact with the respective 75 wheels, oppositely-movable devices coacting with said pawls to render the latter active and idle in alternate succession, operative connections between said devices and the clutch, operative connections between said latch device and one of said pattern mechanisms, and trip devices between the other pattern mechanism and the shipper mechanism.

13. In a knitting-machine, provided with narrowing and widening mechanism, the combination with the needle-cylinder, the cam-cylinder, the driving-shaft geared with the latter, fast and loose pulleys on said shaft, a driving-belt, a shipper therefor, means whereby said shipper is held normally adjacent to the loose pulley, means whereby it may be 95 temporarily held adjacent to the fast pulley, a pinion fixedly connected with the latter pulley, a secondary shaft, a wheel on the latter geared with said pinion, a crank on said secondary shaft, a radius-bar connected therewith carrying a sector, a pinion loosely mounted on the main shaft and geared with said sector, a clutch, means whereby it is normally held in position to lock the fast pulley to the shaft, a latch device whereby said clutch may 100 be temporarily engaged with the pinion last named, a trip device for the shipper, a trip device for the said latch, and pattern mechanism for actuating said trip devices at predetermined intervals.

14. In a knitting-machine, provided with narrowing and widening mechanism, the combination with the needle-cylinder, the cam-cylinder, the driving-shaft geared with the latter, fast and loose pulleys on said shaft, a 115 driving-belt, a shipper therefor, means whereby said shipper is held normally adjacent to the loose pulley, means whereby it may be temporarily held adjacent to the fast pulley, a pinion fixedly connected with the latter pulley, a counter-shaft, a wheel on the latter geared with said pinion, a crank on said counter-shaft, a radius-bar connected therewith carrying a sector, a pinion loosely mounted on the main shaft and geared with said sector, a clutch, means whereby it is normally held in position to lock the fast pulley to the shaft, a latch device whereby said clutch may 120 be temporarily engaged with the pinion last named, a rock-shaft, operative connections between the same and the radius-bar, independently-movable ratchet-wheels on said rock-shaft, pattern mechanisms adapted to be intermittently actuated by said wheels, arms

on said rock-shaft carrying pawls adapted to coact with the respective wheels, means for rendering said pawls active and inactive in alternate succession, operative connections 5 between said latch and one of said pattern mechanisms, and trip devices between the other pattern mechanism and the shipper mechanism.

15. In a knitting-machine, the combination 10 with the cam-cylinder and the needle-cylinder having provision for vertical adjustment, of a driving-shaft, gearing between the same and the cam-cylinder, means for imparting continuous rotary movement to said shaft, means 15 for imparting reciprocating rotary movement to said shaft, a clutch member whereby either of said means may be thrown into or out of action in respect to the shaft, as desired, a hand-lever for controlling said clutch member, a rock-shaft connected therewith, and adapted to be rocked thereby, a vertically-swinging lever constructed and arranged to effect the adjustment of the needle-cylinder, and means on said rock-shaft coacting with 25 said lever to control the position thereof when the rock-shaft is actuated.

16. In a knitting-machine, the combination 20 with the cam-cylinder, the needle-cylinder, and a vertically-movable support for the lat- 30 ter cylinder, of a driving-shaft, gearing between the same and the cam-cylinder, means for imparting continuous rotary movement to said shaft, means for imparting reciprocating rotary movement to said shaft, mechanism 35 whereby either of said means may be rendered active or inactive in respect to the shaft, a lever adapted to coact with the movable support, a rock-shaft, a link connection between the same and the said lever, and mechanism 40 for actuating said shaft at predetermined intervals.

17. In a knitting-machine, the combination 45 with the cam-cylinder, the needle-cylinder, and a vertically-movable support for the lat-

ter cylinder, of a driving-shaft, gearing be- 45 tween the same and the cam-cylinder, means for imparting continuous rotary movement to said shaft, means for imparting reciprocating rotary movement to said shaft, mechanism whereby either of said means may be rendered 50 active or inactive in respect to the shaft, a lever adapted to coact with the movable support, a rock-shaft, an adjustable arm on one end of said shaft, means for adjusting the same, a connection between said arm and the lever, and pattern mechanism for actuating said rock-shaft at predetermined intervals.

18. In a knitting-machine provided with narrowing and widening mechanism, the combination with the needle-cylinder, the cam- 60 cylinder, the driving-shaft geared with the latter, fast and loose pulleys on said shaft, a driving-belt, a shipper therefor, means whereby said shipper is held normally adjacent to the loose pulley, means whereby it may be 65 temporarily held adjacent to the fast pulley, a reciprocating rotary mechanism, gearing between the same and the fast pulley, a clutch whereby the said reciprocating mechanism and the fast pulley may be thrown into and 70 out of action in respect to the shaft in alternate succession, means whereby said clutch normally locks the fast pulley to the shaft, a latch device whereby said clutch may be temporarily engaged with the reciprocating mech- 75 anism, a trip device for the shipper, a trip device for the said latch, and pattern mechanisms for actuating said trip devices at predetermined intervals, together with means for temporarily locking the clutch in idle posi- 80 tion.

In testimony whereof I have hereunto affixed my signature in the presence of two subscribing witnesses.

HENRY BRINTON.
